(57) **CLAIM**

The ornamental design for a mounting hitch with carrier arm and mower unit, as shown and described.

DESCRIPTION

FIG. 1 is a front isometric view of a mounting hitch with carrier arm and mower unit, showing my new design.

FIG. 2 is a rear isometric view thereof.

FIG. 3 is a front elevational view thereof.

FIG. 4 is a rear elevational view thereof.

FIG. 5 is a left side elevational view thereof.

FIG. 6 is a right side elevational view thereof; and,

FIG. 7 is a top plan view thereof.

The broken lines in the figures depict environmental features that form no part of the claimed design.

1 Claim, 7 Drawing Sheets
